UNITED STATES PATENT OFFICE.

ANTOINE CIERPLIKOWSKI, OF PARIS, FRANCE.

HAIR-CURLING DEVICE.

Application filed December 6, 1927. Serial No. 238,055.

My invention relates to a new and improved electrically heated device for treating the hair. This device is particularly adapted for use in curling or waving hair, but it is applicable to a great many other uses.

One of the objects of my invention is to provide a device of this type which can be quickly and conveniently used.

Another object of my invention is to provide a type of this kind which shall be simple and efficient and which shall be cheap to manufacture and assemble.

Another object of my invention is to provide a device whereby electrically heated elements are held by a spring.

Another object of my invention is to provide a device of this type in which the heating elements shall be tightly clamped against the exterior of the lock of hair which is being treated.

Other objects of my invention will be set forth in the following description and drawings which illustrate a preferred embodiment thereof, it being understood that the above general statement of the objects of my invention is intended to generally explain the same and not to limit it in any manner.

Fig. 1 is a side elevation.

Fig. 2 is an end elevation.

Fig. 3 is a top view of the spring which forms part of the device.

Fig. 4 is a side view of the spring.

Fig. 5 is a detail front elevation of one of the heating members and the parts connected thereto.

Fig. 6 is a cross-sectional view of one of the heating members.

As shown in detail in Fig. 6 each heating member A comprised a metal shell or casing which is provided with an interior resistance G of any suitable type which is heated to the proper temperature when an electric current is passed through it. The resistance G is provided with a layer of heat insulating fibre F which may either partially or completely cover said resistance G so as to protect the hair more or less from the heat generated in the resistances G. The resistance G is provided with a cover shell H. The said heating member A is provided with an arm or stem B.

The shells of heating elements A are suit-

ably enameled or vitrified so that they are electrically insulated and the said elements A are thus electrically insulated. Each heating element A is connected to a clamping stem B may of any suitable metal and which is stamped or cast so as to have reinforcing ribs C in order to give it greater rigidity. Each stem B is connected to a plug element D which holds in proper position the conducting wires for leading the current to the resistances G.

A pair of the stems B are led through the recesses E of a curved blade spring R so that when the parts are assembled, they have the relative position shown in Fig. 2. The ends of the curved spring R engage the clamping element A so that said clamping elements are in the position shown in Fig. 2. The stems B may fit frictionally in openings E.

It is obvious that by forcing the stems B towards each other, the space between the adjacent clamping elements is increased.

In curling a lock of hair, it is customary to wind it in spiral form around a central tube.

The shells of the heating elements can thus be directly clamped upon the spirally wound lock so that the heat is communicated directly thereto without any intervening hair spaces or the like. This enables the use of a relatively low temperature because the heat produced by the resistances G is directly transmitted to the shells which are in direct contact with the spirally wound hair.

I have described a preferred embodiment of my invention, but it is clear that numerous changes and omissions could be made without departing from its spirit.

I claim:

1. A heating device for treating the hair comprising a plurality of electrically heated elements and a curved blade spring connected to said elements and adapted to force them towards each other.

2. In combination a curved blade spring having a pair of openings therein, a pair of heating elements located between the ends of the said blade spring and stems connected to said heating elements and extending through said openings.

In testimony whereof I affix my signature,

ANTOINE CIERPLIKOWSKI.
